UNITED STATES PATENT OFFICE.

GUSTAVE A. HENCKEL, OF NEW YORK, N. Y.

DESIGN FOR A VASE AND CANDLE-LAMP.

49,518.

Specification for Design.

Patented Aug. 15, 1916.

Application filed March 18, 1914. Serial No. 825,704. Term of patent 14 years.

To all whom it may concern:

Be it known that I, GUSTAVE A. HENCKEL, a citizen of the United States of America, residing at New York, in the county of New York and State of New York, have invented a new, original, and ornamental Design for a Vase and Candle-Lamp, of which the following is a specification, reference being had to the accompanying drawing, forming part thereof.

The said design is shown in the accompanying drawing, which illustrates the vase and candle lamp in elevation.

Copies of this patent may be obtained for five cents each, by addressing the "Commissioner of Patents, Washington, D. C."

I claim:

The ornamental design for a vase and candle lamp as shown.

In testimony whereof I have signed this specification in the presence of two subscribing witnesses.

GUSTAVE A. HENCKEL.
